ALEXANDER MCLEAN NICOLSON, OF NEW YORK, N. Y., ASSIGNOR, BY MESNE ASSIGNMENTS, TO WIRED RADIO, INC., OF NEW YORK, N. Y., A CORPORATION OF DELAWARE

MULTIPLE PIEZO-ELECTRIC TRANSFORMER

Application filed March 11, 1927. Serial No. 174,488.

This invention relates to piezo-electric crystal devices, and more particularly to such devices adapted to be used as transformers and particularly adapted to be used for coupling thermionic relays to other devices or to each other, and more particularly, relates to improvements on the arrangements described and claimed in my copending application entitled "Piezo-electric coupling", Serial No. 155,896, filed Dec. 20th, 1926, and my Patent No. 1,829,234 of October 27, 1931, entitled "Piezo-electric transformers".

It is an object of this invention to provide piezo-electric apparatus which will afford, with respect to electromotive forces or currents impressed upon the input or motor apparatus, and derived from the output, or generator apparatus, not only the desired ratio between potentials or currents, but will afford also, different resonant conditions in the different devices and different phasing of electromotive forces and resulting currents, whereby crystal devices having various characteristics may be associated in operation to produce various desired effects such for instance as a transformer having a flat response characteristic over a certain range of frequencies.

It is a further object of this invention to provide piezo-electric apparatus comprising a plurality of piezo-electric crystal devices, associated together in various ways for operation to produce the desired output characteristics, particularly adapted for coupling thermionic relays to other devices, or to each other.

It is still a further object of this invention to provide a thermionic relay system utilizing a plurality of thermionic relays coupled in cascade, in which the coupling means comprises a piezo-electric crystal system, having the desired characteristics. Still other objects of this invention will be apparent from the specification.

45 The features of novelty which I believe to

be characteristic of my invention are set forth with particularity in the appended claims. My invention, itself, however, both as to its fundamental principles and as to its practical embodiments will best be understood by reference to the specification and accompanying drawings, in which:

50 Fig. 1 is a diagrammatic view of a system in accordance with my invention, showing one arrangement of the piezo-electric elements.

Fig. 2 is a detail view showing a modified arrangement of the piezo-electric elements.

Fig. 3 is a similar view showing a different arrangement which may be employed.

Fig. 4 shows still a further arrangement.

Figs. 5 and 6 show still further arrangements.

In my copending application entitled "Piezo-electric coupling", Serial No. 155,896, filed Dec. 20, 1926, and "Piezo-electric transformers", Serial No. 163,325, filed Jan. 25th, 1927, I have shown and described arrangements for coupling circuits by means of piezo-electric elements and more particularly in the latter application I have shown and described an arrangement which I term a "piezo-electric transformer" utilizing a piezo-electric motor crystal driven by electrical oscillations in one circuit and producing mechanical stresses thereby. The mechanical stresses are impressed upon a second piezo-electric crystal forming a generator element and the electrical oscillations resulting from the mechanical stresses applied thereto, are utilized to initiate or control the oscillations in the circuit desired.

70 In accordance with this invention, I have provided arrangements for controlling the energy transfer characteristics of a piezo-electric transformer in order to obtain any desired characteristics.

75 In accordance with this invention, I may utilize a plurality of crystal devices associating electrically in any desired manner with a

source of electrical oscillations and operated thereby to produce mechanical stresses. The mechanical stresses may be applied to a plurality of generator crystals which are linked together electrically, and the characteristics of the individual crystals, either motor or generator, and the association, either electrical or mechanical, may be so chosen as to afford the desired over-all characteristics. For example: The motor crystals may be electrically connected either in series or in parallel, and they may be either mechanically associated or insulated; likewise, the generator crystals may be so arranged. Furthermore, the crystals may be arranged mechanically either in series or in parallel, or in what I may term "horizontal or vertical chains". In any event, it will be seen that a wide range of characteristics may be obtained by the proper selection of one or more of all of the variable factors as pointed out above.

Referring now more particularly to Fig. 1, I have shown an arrangement utilizing one form of piezo-electric transformer for coupling thermionic relays. In this figure, S represents a source of electrical oscillations. 1, 2 and 3 designate piezo-electric crystal motor elements, such for example as crystals of Rochelle salt exhibiting the "hour glass" configuration, and provided with electrodes 4 and 5, 6 and 7, and 8 and 9, respectively. The electrodes may take any desired form, such for example as an internal electrode formed within the crystal, and an external electrode applied thereto, or a pair of external electrodes applied at opposite electrical poles, or in fact, any desired arrangement useful for the purpose. Electrodes 5 and 6 are connected together as are electrodes 7 and 8, and electrodes 4 and 9 are connected to a source of electrical oscillations such for example as the output circuit for a thermionic relay or other circuit affording electrical oscillations which it is desired to impress upon the thermionic amplifier 26. A plurality of piezo-electric crystal generator elements are provided such as 10, 11, 12, 13 and 14, having electrodes 16 and 17, 18 and 19, 20 and 21, 22 and 23, and 24 and 25 respectively. The electrode 16 may be connected to the grid or control electrode 27 of the thermionic relay 26 having a filamentary cathode 28 adapted to be heated by a suitable source of energy such as filament battery 30. The electrode 25 may be connected to the filament circuit. A series connection may be made between electrodes 17 and 18, 19 and 20, 21 and 22, and 23 and 24, as shown, whereupon as will be apparent, the input circuit of the thermionic relay 26 will include crystal devices 10, 11, 12, 13 and 14, in series. The output circuit of thermionic relay 26 comprising anode 29 and a suitable source of potential 31, may include a similar piezo-electric transformer system 32, the secondary of which

is connected in the input circuit of the thermionic relay 33 by means of a connection to the grid or control electrode 34 and to the filament 35, and the output circuit of which may comprise the anode 36, a suitable indicating instrument which may be a pair of telephone receivers 39, and the usual battery or other source of potential 37.

It will be noted in this instance, the motor crystals 1, 2 and 3 are mechanically associated with each other and are electrically connected in series. It will also be observed that generator crystal devices 10 and 11 are mechanically associated directly with motor crystal 1 but indirectly with the crystals 2 and 3, as a result of the mechanical connection between all of the motor crystals.

It will be understood that the phase of operation of any one of the crystals may be reversed by reversing the connections to the electrodes and it will also be understood that the amplitude and frequency characteristics of the individual crystals may be controlled by the mechanical association between the crystals; for example, application of stresses to the crystal 10 at a different point from that shown, may result in the vibration of the crystal device 10 in a different mode and at a different frequency or frequencies.

Referring now more particularly to Fig. 2, I have shown a source of electrical oscillations S, the motor crystals 1, 2 and 3, as electrically connected in parallel instead of in series, and free mechanically with respect to each other, and likewise associated in a different manner with respect to the generator crystals 10, 11, and 12. It will be understood, however, that if desired, any one of the crystals 1, 2 and 3 may be mechanically associated with another, and the association of the generator crystal or crystals with their respective motor crystals may be changed as desired.

Referring now to Fig. 3, I have shown still a different arrangement in which the motor crystals 1, 2 and 3 are connected to the source of electrical oscillations S as in Fig. 2 but in which the generator crystals 10, 11 and 12 are mechanically associated with the motor crystals in still a different manner, and are coupled inductively to the input circuit of the amplifier system 26 by means of coils 45, 46 and 47 respectively, connected between electrodes 16 and 17, 18 and 19, and 20 and 21: Each of these coils is inductively coupled to coil 48, 49 and 50 respectively, which are connected in series or in parallel if desired, and to the input circuit of the amplifier system 26.

Referring now more particularly to Fig. 4, I have shown a system similar to that shown in Fig. 2 except that the motor crystals 1, 2 and 3 are mechanically associated with each other as in Fig. 1. In this instance, however, a portion of the energy of the output

circuit of the amplifier system which may comprise any number of stages as desired, is fed back into the input side of the motor crystals for the purpose of reinforcing the oscillations in said circuit to the extent, if desired, of producing sustained oscillations.

Referring now more particularly to Fig. 5, I have shown an arrangement in which there are provided not only motor crystals 1, 2 and 3, but additional motor crystals 51, 52 and 53 having electrodes 54 and 55, 56 and 57, and 58 and 59 respectively, mechanically associated in series with the crystals 1, 2 and 3 respectively, and forming what I may term a "vertical chain" for operating the generator crystals 10, 11 and 12, whereas the arrangement shown in Fig. 1, I term a "horizontal chain". In this instance, all of the motor crystals are shown as electrically connected in parallel, but it is to be understood that any desired electrical connection may be provided. The mechanical association of motor crystals 51, 52 and 53 and generator crystals 10, 11 and 12 respectively, is similar to that shown in Fig. 3, but the circuit including these crystals is shown as coupled to the input circuit of the amplifier system by means of coils 60 and 61 inductively coupled to each other instead of by a direct connection.

The output circuit of the amplifier may be connected to a suitable work circuit by means of coils 62 and 63 arranged in inductive relation and a suitable amount of energy may be fed back to the input circuit of motor crystals 1, 2 and 3 by means of coil 64 in inductive relation with coils 62 and 63. By a suitable adjustment of the phase and intensity of the energy fed back, it will be understood that sustained oscillations may be produced in the system. It will be understood that by arrangements of the various crystal devices for particular modes of vibration and particular association with each other, as shown and described in my application entitled "Orientation of component crystals in composite piezo-electric devices", Serial No. 155,902, filed Dec. 20, 1926, as well as by choice, of the nature and characteristics of the individual crystals and their electrical association with each other, it is possible to provide a wide variation in the characteristics of the system.

Referring now more particularly to Fig. 6, I have shown still a further arrangement which may be utilized. In this figure, 70 designates a suitable source of electrical oscillations impressed upon the input circuit of a thermionic relay 71 of the usual type, comprising control electrode 72, filamentary cathode 75 energized by suitable battery 76, and anode 74 energized by a suitable source such as battery 77 through a suitable choke 78. Motor crystal 79 may be arranged having its electrodes 80 and 81 connected in the output circuit of the thermionic relay 71. Suitable generator crystal 82 is mechanically

associated with the motor crystal 79, and a pair of motor crystals 85 and 86 are arranged to be mechanically and electrically vibrated by the generator crystal 82 which I may term the "master generator crystal." The motor crystals 85 and 86 are provided with electrodes 87 and 88, and 89 and 90 respectively, which electrodes are connected in parallel as shown, or in series, if desired, with electrodes of the generator crystal 82. A pair of generator crystals 91 and 92 are also provided, mechanically associated with motor crystals 85 and 86, and provided with electrodes 93, 94, 95 and 96 respectively. In case the frequency characteristics of these crystals are different, tuning means 97 and 98 may be provided for maintaining a separation of the frequencies, if desired; and the output of the entire system may be impressed upon the input circuit of a suitable thermionic amplifying system 100.

It will be seen that in the arrangement shown, the stresses developed in the master motor crystal 79 are passed through the master generator crystal 82, the motor crystals 85 and 86 to the generator crystals 91 and 92, but it will be understood that if desired, the crystal 82 may be separated from the crystals 85 and 86, whereby the final motor-generator systems will be electrically, but not mechanically, associated with the master motor generator system. As before, by selecting or controlling the characteristics of the individual crystals and the manner of their association, both electrical and mechanical, it is possible to obtain widely different output characteristics.

While I have shown and described certain preferred arrangements of the apparatus according to my invention, it will be understood that modifications and changes may be made without departing from the spirit and scope of my invention as will be understood by those skilled in the art.

I claim:

1. A piezo-electric transformer comprising a piezo-electric crystal device upon which an electromotive force of certain characteristics may be impressed, means for impressing said electromotive force thereon, a plurality of other piezo-electric crystal devices each having a frequency characteristic different from the others mechanically associated with the first said crystal device, and means to derive an electromotive force of characteristics different from the first said electromotive force as a composite output from the last said crystal devices.

2. A piezo-electric transformer system comprising in combination a plurality of piezo-electric transformers having frequency characteristics different from one another, each comprising a piezo-electric crystal motor element, and a piezo-electric crystal generator element mechanically driven thereby,

electrical connections between the motor crystals of each transformer, means for impressing actuating forces on said motor crystals, and means for integrating the effects thereof in said piezo electric crystal generator elements.

3. A piezo-electric transformer system comprising in combination a plurality of piezo-electric transformers, each transformer having a frequency characteristic peculiar to itself and comprising a piezo-electric crystal motor element and a plurality of piezo-electric crystal generator elements driven thereby, and electrical connections between the generator crystals of each transformer for integrating the effects of said motor element upon each of said generator crystals.

4. A piezo-electric transformer system comprising in combination a plurality of piezo-electric transformers having frequency characteristics different from one another, each transformer comprising a piezo-electric crystal motor element and a piezo-electric crystal generator element, and electrical connections between the motor crystals of each transformer and between the generator crystals of each transformer for integrating the effects of said generator crystals in accordance with the operation of said motor crystals.

5. A piezo-electric transformer system comprising in combination a plurality of piezo-electric transformers, each transformer comprising a piezo-electric crystal motor element and a piezo-electric crystal generator element driven thereby, and electrical connections establishing a series circuit through the generator crystals of each transformer.

6. A piezo-electric transformer system comprising in combination a plurality of piezo-electric transformers, each transformer comprising a piezo-electric crystal motor element and a piezo-electric crystal generator element driven thereby, and connections establishing a parallel circuit through the motor crystals of each transformer.

7. A piezo-electric transformer comprising in combination a piezo-electric crystal device, means for impressing electromotive forces thereon, and a plurality of piezo-electric crystal devices associated with said first device in a manner to be stressed by vibrations thereof, said piezo-electric crystal devices having differing characteristics, a circuit including said first mentioned piezo-electric crystal device and an independent circuit including said plurality of piezo-electric crystal devices.

8. A piezo-electric transformer system comprising in combination a plurality of piezo-electric transformers, each transformer comprising a piezo-electric crystal

motor element and a piezo-electric crystal generator element driven thereby, and electrical connections between corresponding crystals of each transformer, said crystals having different frequency characteristics and operating to receive variable electrical currents at each motor element and modify the effect thereof at each generator element.

9. A piezo-electric transformer system comprising in combination a plurality of piezo-electric crystal devices, each of said devices including at least one motor element and one generator element having different characteristics, a circuit common to all of said motor elements for impressing a variable electromotive force thereon, and a circuit common to said generator element for delivering an electromotive force of modified character with respect to the applied electromotive force.

10. A piezo electric transformer system comprising a plurality of piezo electric transformers of differing frequency characteristics, each transformer comprising a piezo electric crystal motor element and a piezo electric crystal generator element driven thereby and electrical connections establishing a parallel circuit through the generator crystals of each transformer.

11. A piezo electric transformer system comprising a plurality of piezo electric transformers having different frequency characteristics respectively, each transformer comprising a piezo electric crystal motor element and a piezo electric crystal generator element driven thereby and connections establishing a series circuit through the motor crystals of the several transformers.

12. A thermionic system comprising a plurality of thermionic relays, means for coupling said relays comprising a piezo electric transformer system including a plurality of groups of electro-mechanically associated piezo electric crystals each group having its own frequency characteristic, one of the crystals of each group being a motor crystal, the other crystal of each group being a generator crystal, the motor crystals being connected in the output circuit of one of the said thermionic relays, and the generator crystals being connected in the input circuit of the other of the said thermionic relays whereby the last said relay is provided with a flat response characteristic over a given range of frequencies.

13. A thermionic system comprising a plurality of thermionic relays, means for coupling said relays in cascade comprising a piezo electric transformer system including a plurality of piezo electric motor and generator elements composed of electro-mechanically associated crystals having differing frequency characteristics, means for delivering energy from one of said relays to the motor crystals of said transformer system, and

means for delivering energy from the generator crystals to the control circuit of the other of said relays, said delivered energy having a frequency characteristic which is the resultant of the frequency characteristics of the several pairs of motor and generator crystals.

Signed at New York city in the county of New York and State of New York this tenth
10 day of March, A. D., 1927.
